MERCURY LAMP VOLTAGE CONTROL

Richard F. Walsh, Lynn, and Joseph Roland Morin, Ipswich, Mass., assignors, by mesne assignments, to Sylvania Electric Products Inc., Wilmington, Del., a corporation of Delaware

Application October 6, 1954, Serial No. 460,546

3 Claims. (Cl. 316—26)

This invention relates to mercury lamps, and in particular to those of the high pressure type, in which the operating voltage is fixed by the vapor density of the mercury.

If the lamp contains more mercury than necessary to give a vapor density corresponding to a predetermined voltage, the voltage will vary widely with changes in the operating temperature of the lamp, and hence with the ambient temperature of the atmosphere around the lamp. It is accordingly customary to put into the lamp a quantity of mercury which when completely vaporized will give the desired voltage, and then to operate the lamp at currents giving a lamp temperature above the temperature at which all the mercury is vaporized. Variations in the lamp temperature will then not vary the lamp voltage unless the variation is so great as to reduce the temperature to a value such that some of the mercury begins to condense out on the tube wall.

The amount of mercury required for the usual voltages is so small, however, that it is difficult to fix it with precision in a lamp and the amount required from lamp to lamp will in any event vary with slight changes in the lamp dimensions.

We have found, however, that the amount can be precisely fixed by operating the lamp with more mercury therein than necessary for the desired voltage, condensing the excess in a portion of an elongated exhaust tube, cooling the lamp and exhaust tube after the lamp voltage has attained a maximum and dropped to the desired value, and then sealing off the exhaust tube between the main lamp envelope and the portion of the exhaust tube in which the mercury has condensed. This also improves lamp performance by the diffusion of residual contaminants into the portion of the exhaust tube which is sealed off.

Other objects, advantages and features of the invention will be apparent from the following specification, taken in conjunction with the appended drawings in which:

Figure 1 is a perspective view of one embodiment of the invention;

Figure 2 is a perspective view of a modified embodiment;

Figure 3 is a view of several of the devices of Figure 2 arranged on a bench;

Figure 4 is a schematic circuit diagram of the lamp circuit;

Figure 5 is a schematic circuit diagram of the exhaust tube heater circuit; and

Figure 6 is a view of the sealing-off of the exhaust tube.

In Figure 1, the lamp envelope 1 which can be of quartz, hard glass, or similar material, is supported by the metal clamps 2, 3 which are attached to its main lead-in wires 4, 5. A third lead-in wire 6, to an auxiliary electrode for starting the lamp, can be left unconnected as shown, if sufficient voltage is available to start

2

the lamp without the use of that electrode. The clamps 2, 3 are attached, respectively, to their supporting metal rods 7, 8 which project from the plug 9, which may be of asbestos or other heat-resistant material.

5 The other two metal conducting rods 10, 11 are connected to the resistance wire 12 in heater 13 which fits over the elongated exhaust tube 14 but is short enough to allow the outer end of the exhaust tube 15 to project therefrom. The heater 13 can comprise a heater wire

10 12 and an enclosing tube of ceramic or other heat resistant material, the tube having a central cylindrical opening through which exhaust tube 14 can pass.

The plug 9 is supported from the heat-resistant plate 16, which also supports the magnet 17 above the lamp

15 envelope 1. The magnet has a coil 18 from which leads 19 and 20 extend to and through the plate 16. A bracket 21 is held to plate 16 and plate 22 by screws 23, and the magnet 17 is attached to the end of plate 22 by the screws 24 through the laminated iron core 25 in coil 18.

20 The metal manifold 26 leads to the air outlets 27, 28 through pipe 29 and valve 66.

The glass outer envelope 30 extends around the inner envelope 1 and fits over the plug 9, to reduce convection losses and to allow the lamp to heat quickly.

25 In Figure 2, the lamp envelope 1 is supported on heat-resistant metal brackets 31, 32 which also serve as connections to lead-in wires 4 and 5. The heat-resistant box 34 surrounds the unit, with the cover 35 on hinges 36, and having the snap-holder to hold it to box 34 when

30 the cover is closed over said box. Openings 37, 38 are left in the bottom of the box for the cooling air. Heater 39 keeps exhaust tubing hot as in Figure 1.

Figure 3 shows several units of the type of Figure 1 set into compartments formed by the backplates 16 and

35 partitions 40 between the units. Metal supports 41 extend upward from the floor (not shown), and the plates 16 are attached to them. They also carry a metal rod 42 which extends in front of the partitions and carries a cloth curtain 43 held thereto by wire loops 44, so that the

40 curtain can be pushed aside while the lamp envelopes 1

are set in place in the partitions, and then pulled back into place to shield the light of the lamps from the observer's eyes.

45 A metal cross-piece 45 supports a panel 46 carrying a voltmeter 47 for each lamp, and the toggle-switches 48, 49 for turning on the lamps and heaters 13, respectively. Another metal cross-piece 50 supports a shelf 51 on which the inductance coils 52 are mounted to serve as ballasts. A variable reactor 53, controlled by knob 54, allows the

50 voltage across the lamps 1 to be varied. Metal lug 56 serves to support the back plate 57.

In Figure 4, the variable reactor or auto-transformer 53 has the variable contact-knob 54 for varying the output voltage which is impressed across the ballast 58, the magnet 59 and the lamp 60 in series. A voltmeter 61 is across the lamp and an ammeter 62 in series with the lamp, as shown.

55 In Figure 5, the circuit to the heater coil 13 is shown, the heater being supplied from the variable auto-transformer 63 through ammeter 64. A voltmeter 65 is across the heater coil 13.

In addition to the features appearing in the drawings, the sealed lamp envelope 1, has the usual electrodes on the internal ends of the lead-in wires 4, 5, and has a filling of argon at about 8 mm. pressure and of mercury, the amount of mercury present being somewhat greater than that necessary to give the desired voltage when completely vaporized.

70 In operation, the lead-in wires 4, 5 of the sealed lamp envelope 1 are secured in the clamps 2, 3, and the heater 13 is placed around exhaust tube 15, the sealed-off end

of the latter extending out of the heater. The open end of outer glass envelope 30 is pushed over plug 9 which holds it in place, and voltage is applied to the lamp circuit of Figure 4 and the heater circuit of Figure 5. The magnet has been previously set in position to hold the arc flame horizontal in the envelope 1, to prevent the flame from touching and cracking said envelope.

As the mercury is vaporized in envelope 1 by the heat of the discharge, the voltage across electrodes 4, 5 will rise and reach a maximum. All the mercury in envelope 1 will then have been evaporated, except for whatever amount may be condensed out in the sealed-off end of exhaust tube 15. The heater 13 is adjusted to keep the mercury from condensing out of envelope 1 too quickly.

If the rate of condensation is too great, the lamp voltage will not reach a maximum during the process, and it will then be uncertain whether or not all the mercury in the lamp envelope 1 has been vaporized. If the lamp voltage reaches a maximum and then drops to the desired value as mercury condenses out, the operator can then be sure that all the mercury in the lamp envelope 1 is vaporized. At the start of the heating, all the mercury should be in the lamp envelope 1, or at any rate the envelope should contain an excess of mercury over that necessary to give the desired lamp voltage, not including any mercury that may be then in the exhaust tube 14.

After reaching a maximum, the voltage will then begin to drop off and when it reaches the desired value for the lamp, the power to the electrodes 4, 5 and to the heater 13 is disconnected. The outer envelope 30 is then removed, and heater 13 is removed from the exhaust tube. The device is then allowed to cool to room temperature. The cooling can be done more quickly if valve 66 is now opened, allowing air to issue from nozzles 26 to be directed onto the lamp. The air-cooling step just described can be omitted if desired, and the lamp allowed to cool in the ambient atmosphere.

The exhaust tube 14 is then sealed off by flames 67 from burner 68 at a point nearer the main portion of the lamp envelope 1 as shown in Figure 6. The excess mercury 69 will be removed with the excess portion 70 of the exhaust tube 14, as in Figure 6, and the amount of mercury remaining in the lamp will be the amount giving the desired voltage.

The same procedure can be used with the enclosing box of Figure 2, the lamp electrodes 4, 5 being secured to the metal supports 31, 32.

In one example of the invention, the lamp envelope 1 was about 7 inches long and 1 $\frac{3}{8}$ inch in diameter, the lead-in wires being .030 inch in diameter and about 1 inch out of the envelope 1. The exhaust tube 14 extended 3 inches out of the lamp at the start of the method and was sealed off about $\frac{3}{16}$ inch from the envelope 1 after the excess mercury had condensed in it.

The internal electrodes were of the usual oxide coated tungsten wire types customary in mercury lamps. A voltage of 220 volts was applied across the lamp for starting, and the series impedance, including the inductance 58 and magnet coil 17, was sufficient to pass a

current of 6 amperes when the arc voltage was 135 volts and the voltage applied to the circuit was 200 volts.

What we claim is:

1. The method of manufacturing a high pressure mercury lamp to have a predetermined operating voltage, said lamp having an envelope, electrodes therein, a quantity of mercury therein and an elongated exhaust tube extending therefrom, said method comprising: passing a current between said electrodes to heat said lamp and to vaporize the mercury therein, the passage of said current being continued until the voltage rises to a maximum and then begins to fall; heating the exhaust tube only in the region nearest to said lamp in order to insure that the lamp voltage rises to a maximum before it begins to fall, and allowing the remainder of the exhaust tube to remain cool; discontinuing the passage of current when the voltage falls to the desired value; allowing the lamp and exhaust tube to cool; then sealing off the exhaust tube at a point such that the mercury condensed in the exhaust tube is sealed out of the lamp.

2. The method of manufacturing a high pressure mercury lamp to have a predetermined operating voltage, said lamp having an envelope, electrodes therein, a quantity of mercury therein and an elongated exhaust tube extending therefrom, said method comprising: placing said lamp with its longitudinal axis horizontal; passing a current between the electrodes to heat said lamp and to vaporize the mercury therein, the passage of said current being continued until the voltage rises to a maximum and then begins to fall; heating the exhaust tube only in the region nearest to said lamp in order to insure that the lamp voltage rises to a maximum before it begins to fall, and allowing the remainder of the exhaust tube to remain cool; discontinuing the passage of current when the voltage falls to the desired value; allowing the lamp and exhaust tube to cool; then sealing off the exhaust tube at a point such that the mercury condensed in the exhaust tube is sealed out of the lamp.

3. Apparatus for predetermining the operating voltage of a high pressure mercury lamp, said apparatus comprising: means for supporting said lamp horizontally and for making electrical connection thereto; means for passing current through said lamp; means for heating a portion only of said exhaust tube; an electromagnet for keeping the arc horizontal in said lamp; means for indicating the voltage across said lamp; and means enclosing said lamp to reduce heat losses therefrom.
